UNITED STATES PATENT OFFICE

DONALD F. WARNER, OF LYNN, MASSACHUSETTS, ASSIGNOR TO GENERAL ELECTRIC COMPANY, A CORPORATION OF NEW YORK

ELASTIC FLUID TURBINE

Application filed July 23, 1931. Serial No. 552,693.

This invention relates to elastic fluid turbines wherein elastic fluid from an extraction stage or from the exhaust or from both an extraction stage and the exhaust is used 5 for industrial purposes. Turbines of this kind are known as automatic extraction turbines, back pressure turbines and combined automatic extraction and back pressure turbines respectively.

10 In these turbines it is desirable to control the flow of elastic fluid to the turbine and from an extraction stage to the next lower stage in terms of pressure in the extraction stage and in the exhaust respectively.

15 The speed of such combined extraction and back pressure turbine may be maintained constant by external means such as a line of constant frequency to which an electric generator driven by said turbine is connected in 20 parallel with other electric generators. The mechanical energy which is transferred from such a turbine to the electric generator at a determined speed depends upon the amount of steam extracted from the extraction stage 25 and the amount of steam passing the exhaust.

The electric generator having a certain load capacity and being driven by such a turbine is liable to be overloaded and damaged if the mechanical energy transferred to the 30 generator exceeds a certain sustained value or, in other words, if the demands for extraction and exhaust steam simultaneously reach certain values, and particularly if both extraction and exhaust steam demand reach 35 a maximum value at the same time.

One object of my invention comprises an improved control mechanism which prevents overload of the electric generator driven by such turbine or, in other words, which limits 40 the mechanical load output of such turbine to a predetermined value so long as initial conditions in the steam or fluid at the throttle are maintained.

45 Another object of my invention consists in the provision of means which render valve

opening actuation of certain pressure responsive means ineffective if the mechanical load output of the turbine has reached such predetermined maximum value.

My invention accordingly comprises the 50 provision of a governor limiting device, hereafter termed "load-limiting device", which automatically stops valve opening action when the mechanical load output of the turbine has reached a certain maximum 55 value regardless of the relative demands for extracted and exhausted steam and providing initial steam or fluid conditions are maintained. My invention also comprises the provision of yieldable connections between 60 one or more pressure responsive devices and a lever mechanism which connects such devices with the valve actuating means.

For a better understanding of what I believe to be novel in my invention attention 65 is directed to the following description and the claims appended thereto.

Referring to the drawings, Fig. 1 illustrates a preferred embodiment of my invention applied to a combined extraction and back pressure turbine; Fig. 2 illustrates a modified arrangement according to my invention, and Fig. 3 illustrates a diagrammatic view of a part of Fig. 1 in different operative positions.

Referring to Fig. 1, 1 indicates the casing of an elastic fluid turbine, 2 indicates the shaft, and 3 indicates one of the bucket wheels. The turbine is illustrated as being viewed from the high pressure end and is 70 partly broken away at different sections. 4 indicates a conduit for admitting elastic fluid to the high pressure end of the turbine, the admission of elastic fluid being controlled by a valve means 5. 6 indicates the exhaust conduit for the turbine and 7 indicates an extraction conduit connected to an intermediate stage of the turbine. In the extraction stage is a valve means 8, a known form of ring valve being illustrated, which serves to 75 80 85 90

control the flow of elastic fluid from the extraction stage to the next lower stage. It is provided with a gear segment 9 with which meshes a short rack 10 connected by a rod 11 to the piston 12 of a fluid-actuated motor. The pilot valve for the fluid-actuated motor is indicated at 13. When ring valve 8 is turned in a clockwise direction it serves to shut off the flow of elastic fluid from the extraction stage to the next lower stage while when it is turned in a counterclockwise direction it is opened further to permit of increase in the flow of elastic fluid from the extraction stage to the next lower stage and 15 to the exhaust. The ring valve is illustrated diagrammatically and by way of example, such arrangements being now known in the art. A valve means of this type is more particularly illustrated and described in the patent to Norton 1,091,078, dated March 24, 1914.

14 indicates a pressure responsive device here shown as being in the form of a corrugated bellows located in a casing 15. Casing 25 15 is connected by a pipe 16 to exhaust-conduit 6. Pressure responsive device 14 is thus subjected to the exhaust-conduit pressure.

Connected to the pressure responsive device is a stem 17 which at its upper end is 30 connected to one end of a floating lever 18. The other end of lever 18 is connected to a speed governor 19 driven from the turbine shaft.

Spring 21 is a tension spring and operates 35 in a direction to oppose the collapsing of corrugated bellows 14. The tension of the spring may be adjusted by turning the nut 20 in sleeve 20^a. When the pressure in exhaust-conduit 6 increases, corrugated bellows 14 is 40 collapsed somewhat moving the left hand end of lever 18 upward, while when the pressure decreases spring 21 serves to lower the left hand end of the lever 18. A rod 22 is pivoted at its upper end to lever 18 and has an abutment 22^a at its lower end. A lever 23 is slidably secured at its left end to rod 22 and is 45 pressed against said abutment by a spring 22^b. The right end of said lever 23 is pivoted on a fixed fulcrum 24. Pivotaly mounted on lever 23 is a bell crank lever comprising arms 25 and 26. Arm 25 is connected by a link 27 to one end of a lever 28. The other end of lever 28 is connected to a suitable fulcrum 29.

Lever 28 is connected by a link 30 to one 55 end of a floating lever 31. The other end of floating lever 31 is connected to the stem 32 of a fluid-actuated motor 33, the stem 34 of the pilot valve of the fluid-actuated motor being 60 connected to floating lever 31 at an intermediate point. The stem 32 is connected to a valve disk 35 of valve means 5.

Lever 23 is connected by a rod 36 to one 65 arm of a bell crank lever 37 pivoted at the end of a bracket 38, the other arm being connected to one end of a floating lever 39. The other

end of floating lever 39 is pivotally connected to an intermediate point of a lever arm 40 pivoted at its lower end on bracket 41 and pivotally connected at its upper end to a rod 42 which forms an extension of piston rod 11. The stem of pilot valve 13 is connected to floating lever 39.

Bell crank lever arm 26 is connected by a link 43 to one arm of the bell crank lever 44 pivoted on a fulcrum common also to lever 23 in line with its pivot 24. The other arm of bell crank lever 44 is pivotally connected to a stem 45 which at its lower end is connected to a corrugated bellows 46 similar to the corrugated bellows 14. Corrugated bellows 46 is located in a casing 47 which is connected by a pipe 48 to the extraction stage conduit 7. Corrugated bellows 46 is thus subjected to the pressure in the extraction stage. The collapsing of corrugated bellows 46 is opposed by an adjustable tension spring 49 arranged in a manner similar to the spring 21.

The operation is as follows:

Assume that the turbine is running, the speed being fixed by some external means and that valve means 35 and ring valve 8 are positioned so that the pressures in the extraction stage conduit and the exhaust-conduit are of the desired value. If now the pressure in the exhaust-conduit increases due to a decrease in fluid demand, for example, corrugated bellows 14 will be collapsed somewhat thereby lifting the left hand end of lever 18 and through link 22 lifting the left hand end of lever 23, the lever 23 turning on its pivot 24. This serves to lift the right hand end of lever 28 thereby lifting the pilot valve of fluid-actuated motor 33 so as to admit actuating fluid to the upper side of the piston of the fluid-actuated motor and permitting it to escape from the lower side. This causes the piston to move downward thereby closing valve means 5 somewhat so as to decrease the amount of elastic fluid being admitted to the turbine. When the piston of the fluid-actuated motor moves downward it lowers the right hand end of floating lever 31 thereby restoring the pilot valve to its former position. Also, when lever 23 moves upward, through rod 36 it turns bell crank lever 37, moving pilot valve 13 toward the left. This serves to admit actuating fluid to the left hand side of piston 12 and permits it to escape from the right hand side thereby moving piston 12 toward the right and effecting a closing movement of the ring valve 8. When piston 12 moves toward the right the pilot valve is restored to its former position through lever arm 40 and the floating lever connection 39.

If the pressure in exhaust conduit 6 decreases then spring 21 effects downward movement of the left hand end of lever 18 and in a manner similar to that already described, effects an opening movement of valve

means 5 and of the ring valve 8. Thus it will be seen that when the exhaust conduit pressure increases, both the high pressure valve means and the ring valve means are closed somewhat, while when the exhaust conduit pressure decreases, both the high pressure valve means and the ring valve means are opened somewhat.

Upon a change in extracted steam demand 10 the extraction pressure governor 45—47 acts to rotate bell crank 44 which in turn rotates bell crank 25—26 in a like rotary direction. A decrease in extracted steam demand causes an increase in stage pressure. The extraction governor bellows travels in a direction toward its high pressure stop. This causes a clockwise movement of the bell cranks, as shown in the drawings. Upward movement of link 27 acts through lever 28, pilot valve 34, 20 piston and rod 32, etc. to move the main controlling valves in a direction toward closing. The grid valve 8 remains undisturbed by any action of the extraction governor so that if, as assumed in this case, constant demand for 25 exhausted steam exists, the flow and pressure at the exhaust will be unchanged as it should be. The pressure governor 14 etc. therefore holds lever 23 in a fixed position during a change in demand for extracted steam only. 30 Thus it is seen that a change in extracted steam demand can occur without disturbance to the conditions at the exhaust of the turbine.

The mechanism so far described may be 35 taken as typical for the control of a combined extraction and back pressure turbine in which load limiting device and a yieldable connection with respect to one pressure responsive device may be provided for the purpose hereinafter set forth. Whereas I have described such a combined extraction and back pressure turbine as comprising a single unit, I wish to have it understood that such turbine may also comprise two separate units, a high 40 and a low pressure unit, mechanically coupled and driving the same generator or generators. My invention also is not limited to steam turbines as it may similarly be applied to other elastic fluid engines, such as mercury vapor turbines.

According to my invention I provide a mechanical load-limiting device which, as already pointed out, automatically prevents further valve opening action when the mechanical load output of the turbine has 45 reached a predetermined value.

This load-limiting device may be provided with respect to a part of the control mechanism, the movement of which is a function of the mechanical load output of the turbine. More particularly I provide the load-limiting device at a definite point of such part of the control mechanism, the movement of which is a function of the mechanical load output and 50 not to any appreciable degree affected by

the ratio of flows from the exhaust and extraction points.

The movements of such part have to satisfy certain conditions which will be more readily understood from the following:

Let us assume that an amount of steam (A+B) be admitted to the turbine, an amount of steam A be extracted from an intermediate stage and an amount

$$B (B = (A+B) - A)$$

be passed through the low pressure part of the turbine. The thermo-dynamic energy of the steam passing through the turbine is partly transformed into mechanical energy. 80 The mechanical energy M_A obtained from the steam amount A passing through the high pressure part of the turbine is proportional to the amount A itself and a constant c_h . This may be expressed in the mathematical form, $M_A = c_h A$ whereby the constant c_h may be a function of the amount A, the pressure drop within the turbine, temperature, etc. For certain conditions such constant will have a definite numerical value which may 85 change if one of said conditions changes. This constant may also be considered as the efficiency factor or the coefficient of transformation (hereafter termed "transformation factor") of the high pressure part of the turbine. 90

In a similar manner the mechanical energy M_B obtained from the steam amount B passing through the entire turbine is,

$$M_B = c_t B$$

wherein c_t is a corresponding constant with respect to the entire turbine.

The total mechanical load output M is equal to the sum of the mechanical energies obtained from both amounts of steam A and B. Thus, $M = M_A + M_B$ or, introducing the above equations, $M = c_h A + c_t B$. In a similar manner it can be proven that.

$$M = c_h (A+B) + c_t B$$

wherein c_h and c_t represent the transformation factors of the high pressure and the low pressure part respectively and wherein (A+B) is the amount of steam passing the high pressure part and B is the amount of steam passing the low pressure part.

Referring to the last equation

$$M = c_h (A+B) + c_t B$$

it will be seen that in the equation $c_h (A+B)$ represents the output of the stages preceding the extraction opening (M_{AB}); $c_t (B)$ represents the output of the stages following the extraction opening (M_B). The equation also indicates a mutual actuation of the lever mechanism under certain conditions. In case the steam demand B of the exhaust changes, it causes an actuation of both the admission valve and the valve before the

low pressure stages, whereas when the demand for extraction steam changes an actuation of the admission valve only is necessary to satisfy such demand.

5 The problem which now presents itself is to find a part of the mechanism of which the motions are indicative to the energy transformations such that a change in total motion m corresponds to a change in mechanical load output M regardless of the relative demands for steam at the extraction opening and at the exhaust. In other words it is required to find that part of the mechanism which acts as a real or imaginary fulcrum during changes in the relative demands for steam at the extraction opening and at the exhaust during which a constant mechanical load output M is being delivered. If now, a point in the lever mechanism can be found such that a motion m_1 corresponds to a mechanical load output change M_{AB} in the stage or stages preceding the extraction opening, and such that a motion m_2 corresponds to a mechanical load output change M_B in the stage or stages following the extraction opening. Then

$$m_1 = k_1 M_{AB} = k_1 c_h (A + B)$$

$$m_2 = k_2 M_B = k_2 c_1 B$$

30 wherein k_1 and k_2 are factors of the lever mechanism involving the efficiencies of the stages preceding and following the extraction opening respectively, and physical characteristics of the governing mechanism.

35 If a definite flow of steam B passing through the stage or stages of the turbine following the extraction opening cause the same change in mechanical load output as another definite flow of steam $(A + B)$ passing through the stage or stages preceding the extraction opening, and if each corresponds to motion m_1 and m_2 respectively of a certain point in the mechanism which are equal, that

45 is,

$$m_1 = m_2$$

then follows

$$k_1 c_h (A + B) = k_2 c_1 B$$

or in another form,

50

$$\frac{k_1}{k_2} = \left(\frac{c_1}{c_h} \right) \left(\frac{B}{A + B} \right)$$

or

55

$$= \frac{1}{\left(\frac{c_h}{c_1} \right)} \left(\frac{B}{A + B} \right)$$

This result shows that the part of the lever mechanism where the load limiting device has to be applied must satisfy the condition

60 according to which the ratio

$$\frac{k_1}{k_2}$$

65 is inversely proportion to the corresponding ratio of the transformation factors.

A point which substantially satisfies this condition is located on the horizontal part 25 of bell crank lever 25, 26 under the assumption that the transformation factors c_h and c_1 are linear functions of the steam amounts A and B respectively and the corresponding physical condition which in fact is approximately true within certain limits.

In the present instance I have shown a load-limiting device between said lever 25 in 75 the simplest form as comprising a fixed plate 50 and an adjustable head screw 51.

It will be understood that there is only one point beneath said lever to which a definite ratio

$$\frac{k_1}{k_2} \text{ or } \frac{c_1}{c_h}$$

applies. Thus, a displacement of the screw in either direction along the length of the lever would correspond to a change of such ratios. In order to make this important feature clear, attention is directed to Fig. 3 in which I have illustrated a part of the lever mechanism in different operative positions with respect to a load-limiting device. AB and CD represent levers corresponding to levers 23 and 25 of Fig. 1 respectively, and S indicates the load-limiting device.

90 Let us assume that the turning movements are such that in a change of disposition of the levers represented by α_1, β_1 and α_2, β_2 occurs without change in mechanical load output. The levers AB and CD in these positions are indicated by A_1B , A_2B and C_1D_1 , C_2D_2 . In

100 such an event the intersection point along the horizontal arm C—D of the bell crank lever is the proper location for the abutment if the load is to be limited to that value. It is shown as preventing any further downward travel of the lever C—D. It, therefore, limits governor travel in a valve-opening direction. The governor limiting device "S" as shown in Fig. 3 is properly set as there is no change in mechanical load output caused by rotation of the lever C—D about the point of engagement of the lever with the limiting abutment.

110 In any other application the relative location of "S" relative to lever CD has to be changed in dependance upon the "transformation factors" of the stages preceding and the stages following the extraction opening, and the physical characteristics of the two valve groups and the design of the interconnecting linkage and lever system.

115 Only the properly applied load-limiting device maintains the maximum mechanical load output substantially constant regardless of the relative steam demand in the high pressure and low pressure part.

125 If the total load of the turbine reaches a predetermined value and vital steam conditions being assumed constant, lever 25 engages the screw 51 which prevents further

80

95

100

105

110

115

120

125

130

opening of valve 5 and limits thereby automatically the total load of the turbine. This limiting action takes place regardless of the relative demand for extracted and exhaust steam.

At such times when the horizontal arm 25 is in abutment with the load-limiting device (50, 51) it is desired to render further valve opening action of the back pressure governor ineffective. This is achieved by the yielding connection 22 between the levers 18 and 23. A decreasing steam pressure in the exhaust pipe effects the pressure responsive device 14 to move the left end of lever 18 downwardly. But this movement is not transferred to lever 27 as rod 22 merely slides downwardly within the end of lever 23, pressing spring 22^b together.

In connection with the operation of the mechanism it will be understood that the lever arm and the connections are so chosen relatively to each other that when lever arm 23 is moved valve means 5 and valve means 8 are opened or closed by amounts such that valve means 8 will normally effect an increase or decrease of flow past it corresponding to the change in flow past valve means 5.

If the pressure in the extraction stage conduit increases bellows 46 is collapsed somewhat thereby turning bell crank lever 44 in a clockwise direction and through link 43 turning the bell crank lever comprising arms 25 and 26 in a clockwise direction. This serves to lift the pilot valve of fluid-actuated motor 33 thereby effecting a closing movement of the valve means 5 to decrease the amount of elastic fluid admitted to the turbine and bring the pressure in the extraction stage back to its equilibrium value, which is substantially its former value.

If the pressure in the extraction stage decreases then spring 49 serves to turn bell crank lever 44 in a counterclockwise direction, thereby effecting an opening movement of valve means 5 so as to restore the pressure to its equilibrium value. When the pressure in the extraction stage varies, it will be seen that no adjustment of the stage valve means takes place, the high pressure valve means only being moved to bring the extraction stage pressure back to normal value. As a result the pressure in the exhaust-conduit will not be disturbed.

If, however, the pressure in the extraction stage decreases and lever 25 is in its abutment position, indicating that the load limit is reached, the pressure governor 46, etc. will move the mechanism and rotate the lever 25 about the abutment as a fulcrum and in a direction tending to increase the flow to throttle and to decrease the flow to exhaust. The load will be maintained at the limit. It is, therefore, seen that the increased extraction demand is satisfied and without an increase in load. It will be further seen that this is ac-

complished by means of reducing further the flow to exhaust, which when the abutment is made is already limited to a value below that necessary to satisfy the existing demand.

A similar action takes place when a decrease in extracted steam demand occurs and pressure rises in the extraction stage, when the lever 25 is in abutment with the governor limit.

In other words, when the yielding link is applied to the link 22 extraction demand is satisfied at the expense of exhaust demand when the governor is "in abutment."

In the event that it is desirable to satisfy the exhaust demand at the expense of the extracted steam demands at times when the governor is in abutment it would be necessary to apply the yielding connection to the extraction pressure governor element.

There are also cases in which yieldable connections may be provided with respect to both the intermediate stage and the exhaust responsive means. In Fig. 2 I have illustrated such an arrangement; like reference characters designate the same parts as in Fig.

1. Link 17, which is positioned by the intermediate stage responsive device, is slidable in a hole of the left end of lever 18 and has an abutment normally pressed against lever 18 by the action of a spring 17b. Link 45, shown at the right side of the drawings, which is positioned by the extraction responsive device, is similarly slidable in a hole provided in one arm of the bell crank lever 44, and has an abutment 45a normally pressed against the bell crank lever by the action of a spring 45b. The operation of this mechanism is the same as that described above, with the exception that it allows a free positioning of the extraction responsive device 46 (see Fig. 1) when lever 28 is in abutment position.

In accordance with the provisions of the Patent Statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States is:

1. The combination with an elastic fluid turbine, a conduit connected to an intermediate stage of said turbine, another conduit connected to the exhaust of said turbine, pressure responsive devices connected to said intermediate stage and said exhaust respectively, a valve mechanism controlling the admission of elastic fluid to the turbine, a valve mechanism controlling the flow of elastic fluid to the exhaust of the turbine, both being adjusted by said pressure responsive devices, and means for limiting the opening action of both valve mechanisms at such times when the

- mechanical load output of said turbine has reached a predetermined value.
2. The combination with an elastic fluid turbine, a conduit to an intermediate stage of said turbine, another conduit to the exhaust of said turbine, pressure responsive devices connected to said intermediate stage and said exhaust respectively, a valve mechanism controlling the admission of elastic fluid to the turbine, a valve mechanism controlling the flow of elastic fluid to the exhaust of the turbine, both being adjusted by said pressure responsive devices, means for limiting the opening action of both valve mechanisms in response to the demands for steam at either the extraction opening or at the exhaust of the turbine, said limiting means being provided at a part of the valve mechanism the motions of which with respect to the mechanical energies obtained from the steam amounts leaving the intermediate stage and exhaust respectively, are inversely proportional to the corresponding transformation factors of the turbine with regard to said steam amounts.
25. 3. The combination with an elastic fluid turbine having a conduit connected to an intermediate stage, valve means controlling the flow of elastic fluid to the turbine, and valve means controlling the flow of elastic fluid from said intermediate stage to the next lower stage, of means responsive to a condition appurtenant to the exhaust leaving the turbine for effecting adjustment of both said valve means in the same direction, means responsive to a condition appurtenant to elastic fluid flowing in said conduit for effecting adjustment of said first-named valve means only, and adjustable means adapted to limit the opening of said valve means controlling the flow of elastic fluid to the turbine in response to demands for elastic fluid at the extraction opening and at the exhaust.
4. The combination with an elastic fluid turbine having a conduit connected to an intermediate stage, valve means controlling the flow of elastic fluid to the turbine and valve means controlling the flow of elastic fluid from said intermediate stage to the next lower stage, of a lever, means connecting both said valve means whereby when said lever is moved both valve means are adjusted in the same direction, means responsive to a condition appurtenant to the exhaust leaving the turbine for moving said lever, means responsive to a condition appurtenant to elastic fluid flowing in said conduit for effecting adjustment of said first-named valve means independently of said second-named valve means, means forming a yieldable connection between said lever and said means responsive to the exhaust conditions, and adjustable means adapted to limit the "opening-travel" of said lever, said yieldable connecting means being adapted to render the action of said exhaust responsive means ineffective if said adjust-

able load-limiting means is in abutment position.

In witness whereof I have hereunto set my hand.
